(57) **CLAIM**

The ornamental design for a satellite radio, as shown and described.

DESCRIPTION

FIG. 1 is a front left perspective view of the present new design for a satellite radio;

FIG. 2 is a front elevational view thereof;

FIG. 3 is a left elevational view thereof, the right elevational view being a mirror image thereof;

FIG. 4 is a top plan view thereof; and,

FIG. 5 is a bottom plan view thereof.

The broken lines showing various features of a satellite radio are for illustrative purposes only and form no part of the claimed design.

The broken lines that define the bounds of the claimed design form no part thereof.

1 Claim, 5 Drawing Sheets
